(57) **CLAIM**

The ornamental design for a generator frame, as shown and described.

DESCRIPTION

FIG. 1 is a top-front-right perspective view of a generator frame;

FIG. 2 is a bottom-front-left perspective view thereof;

FIG. 3 is a bottom-rear-left perspective view thereof;

FIG. 4 is a top-rear-right perspective view thereof;

FIG. 5 is a front elevation view thereof;

FIG. 6 is a rear elevation view thereof;

FIG. 7 is a left elevation view thereof;

FIG. 8 is right elevation view thereof;

FIG. 9 is a top plan view thereof; and,

FIG. 10 is a bottom plan view thereof.

The broken lines shown represent the portions of the generator frame that form no part of the claimed design.
